[57] CLAIM

The ornamental design for a tractor tool box, substantially
as shown and described.

DESCRIPTION

FIG. 1 is a perspective view of the tractor tool box,
viewed from the left front of my new design;
FIG. 2 is a front elevational view thereof;
FIG. 3 is a rear elevational view thereof;
FIG. 4 is a side view of the left side of FIG. 2;
FIG. 5 is a side view of the right side of FIG. 2;
FIG. 6 is a top view of FIG. 2; and
FIG. 7 is a bottom view of FIG. 2.
